INVENTOR

Vincent Di Figlia.
BY *Marvin Almy*

ATTORNEY

UNITED STATES PATENT OFFICE.

VINCENT DI FIGLIA, OF BROOKLYN, NEW YORK.

COMBINATION MATCH-BOX HOLDER AND CIGAR CUTTER.

Application filed April 22, 1925. Serial No. 24,934.

To all whom it may concern:

Be it known that I, VINCENT DI FIGLIA, a citizen of the United States, residing at Brooklyn, in the county of Kings and State 5 of New York, have invented certain new and useful Improvements in Combination Match-Box Holders and Cigar Cutters, of which the following is a specification.

This invention relates to improvements in 10 smoker's utensils, especially pertaining to ash trays, match holders, cigar rests and cigar cutters.

One of the principal objects of the invention is to so construct an ash tray as to embody 15 with it a cigar cutter which is readily accessible at all times and may be conveniently manipulated.

Another feature of this device is to secure the cutter upon the ash tray so that the 20 waste or cut off portion of the cigar is received within the tray as it drops off the cigar and not upon the floor or surroundings.

A still further aim is to produce a utensil 25 comprising an ash tray combining several adjunctive features so constructed as to preserve a neat and ornamental appearance, of relatively cheap construction and easy manipulation.

30 These several aims and objects are accomplished by the novel construction, combination and arrangement of parts hereinafter described and shown in the accompanying drawing, forming an essential part of this disclosure, and in which:—

Figure 1 is a front elevational view of an embodiment of the invention.

Figure 2 is an end view of the same.

40 Figure 3 is an enlarged transverse sectional view taken on line 3—3 of Figure 1.

Figure 4 is a front elevational view of the same, parts being broken away to show the construction of the interior.

45 Referring more in detail to the drawing, the numeral 10 designates in general an ash tray of ovoidal shape having flat overhanging edges 11 encircling the upper edge of the tray.

Secured at each end of the tray 10 on the 50 edges 11, by solder or other means, are cigar or cigarette rests 12 arcuately curved to conform to the shape of a cigar.

55 Midway in length of the tray 10 on the edge 11, is secured a short post 14 and fixed on the upper end of the post 14, is a plate 17 having a raised spring side 18, the other

side 19 being bent outward at an angle 20 for a portion of its length and then inwardly as at 21 to the height of the side 18.

Engaged over the edge of the angular side 60 21 is a lip 22, formed on a plate 23, having lugs 24, set in the plate 17 and sides 25 enclosing a space in which is slidably mounted a cutter blade 26, slidably engaged on its upper edge in a slot, formed by a guide 65 strip 27, fastened to the inner surface of the plate 21, the lower edge of the blade 26 having a lug 28, slidably engaged in a slot 29 in the plate 21.

The blade 26 is held normally at one end 70 of the device by means of a spring 30, having one end attached to hook 31 on the plate 23, the other end of the spring being engaged by a hook 32, fastened to the plate 26.

A hole 32 in the blade 26 and a similar 75 hole 34, in the plate 21, admits of inserting the end of a cigar, the edges of the holes being bevelled to act as shears, severing the ends of an entered cigar when the cutter blade 26 is pressed inwardly to oppose the 80 spring 30, as will be readily understood, the clipped portion passing out through an opening in the plate element 20.

A narrow stop plate 35, having a raised 85 central arch, is disposed between the plates 23 and 18, being secured by bent lugs 36 to the plate 17, the spring side plate having its upper edge, slightly out-turned to facilitate the entrance of a common safety match box between the plates 18 and 23, the box resting 90 on the stop 35 in a well known manner.

From the foregoing it will be seen that a commodious device for smoker's use has been disclosed, that is readily portable, convenient and of good appearance.

Having thus described my invention, what I claim as new and desire to secure by Letters Patent, is:—

A match box holder and cigar cutter comprising a metal plate bent to produce a 100 flooring for a match box, a vertical side wall, an opposed side wall bent angularly outward and inward at an included angle of approximately ninety degrees, its upper edge being disposed substantially level with the corresponding edge of the first named wall, a plate attached to the upper edge of said angular wall and to its junction with said flooring to extend vertical therebetween, end walls formed with said vertical plate to extend coincidentally with the 105 angular walls, the lower of said angular 110

walls having a discharge opening and the upper of said angular walls having an opening receptive of the end of a cigar, a shear plate slidably engaged closely adjacent the 5 inner surface of said upper angular wall, said shear plate having an opening registerable with the opening in the angular wall,

and a spring co-operatively acting between said shear plate and angular wall whereby the shear plate is held normally extended 10 and the mentioned opening in register.

In witness whereof I have affixed my signature.

VINCENT DI FIGLIA.
